UNITED STATES PATENT OFFICE

162,919

BOTTLE CAPPING MACHINE

Willy E. Zimmermann, Chicago, Ill., assignor to
Standard Cap and Seal Corporation, Chicago,
Ill., a corporation of Virginia

Application July 29, 1949, Serial No. 4,193

Term of patent 14 years

(Cl. D2—3)

To all whom it may concern:

Be it known that I, Willy E. Zimmermann, a citizen of the United States, residing at Chicago, State of Illinois, have invented a new, original, and ornamental Design for a Bottle Capping Machine, of which the following is a specification, reference being had to the accompanying drawing, forming a part hereof. The dominant features of my design reside in the portions shown in full lines.

Fig. 1 is a front perspective view of a bottle capping machine, showing my new design.

Fig. 2 is a rear perspective view thereof.

Fig. 3 is a side perspective view thereof.

I claim:

The ornamental design for a bottle capping machine, as shown and described.

WILLY E. ZIMMERMANN.
